UNITED STATES PATENT OFFICE.

OSCAR RIGHTER, OF PHILADELPHIA, PENNSYLVANIA, ASSIGNOR TO DORNAN BROS. & CO., OF SAME PLACE.

DESIGN FOR A CARPET.

SPECIFICATION forming part of Design No. 14,630, dated February 5, 1891.

Application filed December 18, 1883. Term of patent 3½ years.

To all whom it may concern:

Be it known that I, OSCAR RIGHTER, of the city of Philadelphia, county of Philadelphia, State of Pennsylvania, have invented and produced a new and original Design for Carpets, of which the following is a specification.

The nature of my design is fully represented in the accompanying photographic illustration, to which reference is made.

I claim—

The design for carpets, as herein shown and described.

OSCAR RIGHTER.
